UNITED STATES PATENT OFFICE.

HENRY BREER, OF SYRACUSE, NEW YORK, ASSIGNOR TO CAROLINE H. BREER, OF SAME PLACE.

APPARATUS FOR DESICCATING ANIMAL MATTER.

SPECIFICATION forming part of Letters Patent No. 286,897, dated October 16, 1883.

Application filed March 9, 1883. (No model.)

To all whom it may concern:

Be it known that I, HENRY BREER, of Syracuse, in the county of Onondaga, in the State of New York, have invented new and useful Improvements in Apparatus for Desiccating Animal Matter, of which the following, taken in connection with the accompanying drawings, is a full, clear, and exact description.

This invention is designed as a further improvement on the apparatus for which I have obtained Letters Patent of the United States, No. 255,925.

My present invention consists, first, in certain novel means of fitting the ends of the combustion-chamber close to the lower portion of the ends of the desiccating-cylinder, so as to confine within the cylinder the substance under treatment and prevent the ingress of the products of combustion to the lower part of the cylinder; and, secondly, in certain peculiarities of the detail construction of the apparatus, all as hereinafter more fully explained, and specifically set forth in the claims.

The invention is fully illustrated in the annexed drawings, wherein Figure 1 is a longitudinal section of the desiccating apparatus. Figs. 2 and 3 are vertical transverse sections, respectively, on lines *xx* and *yy* in Fig. 1; and Fig. 4 is a rear end view of the same.

Like letters of reference indicate corresponding parts in all the figures.

A denotes the fire-arch or furnace of the apparatus, and *B* the combustion-chamber arranged back of and in direct communication with the fire-arch in the usual manner.

C represents the horizontal rotary desiccating-cylinder, constructed of heavy sheet metal or boiler-iron, mounted on spiders *S*, which are formed with a peripheral rim, *r*, onto which the ends of the cylinder lap and are firmly secured, said spiders being provided with trunnions *t*, by which the cylinder is journaled in suitable bearings attached to the end walls of the combustion-chamber, the trunnion at the rear end of the combustion-chamber being extended through the end wall, and provided with a pulley or gear, *P*, which, by suitable connections with the motor, transmits rotary motion to the cylinder *C*, said cylinder being provided internally with the usual cross-

chains, *d*, which serve to stir and break up the substance in process of desiccation. The rims *r* of the spiders *S* project beyond the end of the cylinder and fit closely to the end walls of the combustion-chamber. To the latter are attached segmental plates *a*, which extend around the bottom and part way up the sides of the rim *r*, and overlap the same and fit closely thereto.

The upper part of the rear end of the combustion-chamber *B* is formed with a recess, *R*, to allow the products of combustion to enter the cylinder *C* at that point, as indicated by arrows in Fig. 1 of the drawings. The opposite end of the combustion-chamber is provided with a smoke-stack or exit-flue, *F*, which communicates with the upper part of the front end of the cylinder *C*, and thus allows the products of combustion to pass directly from end to end of the upper part of the cylinder.

D denotes a chute, which extends from above the combustion-chamber downward and communicates with the upper portion of the front end of the cylinder, said chute being provided with a cover, *c*, to prevent the products of combustion from escaping through it, the substance to be treated being introduced to the cylinder *C* through the aforesaid chute *D*. At the bottom portion of the opposite end of the cylinder *C* the end wall of the combustion-chamber is provided with a discharge-opening, *E*, through which the desiccated substance escapes from the cylinder, a suitable door being placed over said opening to prevent the escape of the heat from the cylinder, and to retain therein the substance until it is in proper condition for removal.

F' represents fire-flues, which are extended from the furnace *A* direct to the stack *F*, to allow the products of combustion to escape directly to the stack without entering the combustion-chamber when desired to obtain access to the latter, or to replenish the same with the substance to be treated. By means of dampers *e e*, applied to said direct flues, the same can be closed to compel the products of combustion to take the circuitous course through the combustion-chamber *B* and cylinder *C*, as represented by arrows in Fig. 1 of the drawings.

Having described my improvements, what I claim as new, and desire to secure by Letters Patent, is—

1. In combination with the rotary open-ended cylinder C, the combustion-chamber B, provided at the upper part of its rear end with the recess R, and having its opposite end fitted closely to the periphery of the cylinder, the segmental plates *a a*, secured to the ends of the combustion-chamber, and the flue F, communicating with the upper part of the front end of the cylinder, substantially as shown and set forth.
2. In combination with the combustion-chamber B, provided, respectively, at opposite ends with the chute D and discharge-open-

ing E, the spiders S, formed with the rim *r*, the cylinder C, mounted on said rim, and the segmental plates *a a*, secured to the ends of the combustion-chamber and fitted closely to the rim *r*, all constructed and combined substantially in the manner described and shown.

In testimony whereof I have hereunto signed my name and affixed my seal, in the presence of two attesting witnesses, at Syracuse, in the county of Onondaga, in the State of New York, this 5th day of February, 1883.

HENRY BREER. [L. S.]

Witnesses:

FREDERICK H. GIBBS,
WILLIAM C. RAYMOND.
